Application September 12, 1936, Serial No. 64,824

Term of patent 7 years

To all whom it may concern:

Be it known that we, Joseph W. Bowersox, a citizen of the United States, residing in Kansas City, in the county of Jackson, State of Missouri, and Stephen J. Blaha, a citizen of the United States, residing in Hinsdale, county of Du Page, State of Illinois, have invented a new, original, and ornamental Design for a Cushion or Similar Article, of which the following is a specification, reference being had to the accompanying drawing, forming part thereof.

Figure 1 of the drawing is a perspective view of a cushion or similar article showing our design; and Fig. 2 is a perspective view, on a larger

scale and partially broken away, showing only the welted fabric covering and one of the tufting buttons.

The distinctive feature of our design resides in the presence of narrow welts extending across the face of the cushion or similar article parallel to each other and spaced apart, each welt lying between parallel welts near each other, and there being tufting buttons along these welts.

We claim:

The ornamental design for a cushion or similar article as shown and described.
